CLAIM

The ornamental design for a holder for a garage door remote control unit, substantially as shown.

DESCRIPTION

FIG. 1 is a perspective view of a holder for a garage door remote control unit showing our new design;
FIG. 2 is a top plan view;
FIG. 3 is a front elevational view;
FIG. 4 is a right side elevational view;
FIG. 5 is a rear elevational view; and
FIG. 6 is a bottom plan view thereof.

FIG. 1

FIG. 2

FIG. 3

FIG. 4
